UNITED STATES PATENT OFFICE.

NICHOLAS J. CELENZA, OF BROOKLYN, NEW YORK, ASSIGNOR, BY MESNE ASSIGNMENTS, TO BRANDES LABORATORIES INC., OF NEWARK, NEW JERSEY, A CORPORATION OF NEW JERSEY.

ELECTRICAL CONNECTION.

Application filed July 25, 1925. Serial No. 46,171.

My invention relates broadly to electromagnetic sound reproducers and more particularly to a construction of terminal block for electromagnetic sound reproducers.

- 5 One of the objects of my invention is to provide a construction of terminal block for electromagnetic sound reproducers, where connections from the exterior of the casing of the sound reproducer may be snapped 10 into mechanical and electrical engagement without the necessity of adjusting individual binding screws against each of the conductors which connect with the electromagnetic sound reproducer.
- 15 Another object of my invention is to provide a terminal block construction for electromagnetic sound reproducers which is particularly adapted for making positive connections between a plurality of conductors 20 leading to the electromagnetic sound reproducer and the windings of the sound reproducer by a resilient gripping action without the requirement of individual adjustment of binding screws heretofore required in the art.

Still another object of my invention is to provide a resilient grip terminal block for terminals leading from flexible conductors into the interior of an electromagnetic 30 sound reproducer, where the terminals are positively gripped by a single movement toward the electromagnetic sound reproducers.

- I have illustrated my invention with particular reference to telephone receivers but it will be understood that my invention is applicable to various constructions of electromagnetic sound reproducers, including 35 loud speakers, table talkers and the like.
- 40 In the application of my invention to telephone receivers a pair of resilient grips are provided for completing connections between the magnet windings interiorly of the electromagnetic sound reproducer and the conducting cords which lead to the sound 45 reproducer. Intermediate the terminals thus provided, I provide a resilient grip sleeve which is arranged to cooperate with a terminal member connecting to an electrostatic shield surrounding the telephone conductors. The electrostatic shield is connected through the intermediate terminal with the casing of the telephone receiver.

My invention will be more clearly under-

stood by reference to the following specification and the accompanying drawings, in which:

Figure 1 is a plan view showing the interior arrangement of a telephone receiver employing the terminal block of my invention; Fig. 2 is a side view showing a telephone receiver equipped with the terminal block of my invention, while the terminal block is indicated by dotted lines; Fig. 3 is a plan view of the terminal block with the resilient connecting members shown therein in dotted lines; Fig. 4 is a front view showing the construction of the terminal block of my invention; Fig. 5 is a detailed view showing one of the cord terminals leading 55 into the telephone receiver casing and gripped within one of the resilient contact members therein; Fig. 6 is a plan view of the intermediate terminal used for completing electrical connections between the electrostatic shield surrounding the telephone receiver cords and the casing of the telephone receiver; Fig. 7 is a cross-sectional view through one of the telephone receiver 60 cord terminals and the resilient grip sleeve by which the terminal is gripped within the terminal block and the upwardly extending lug which makes connections with the magnet windings interiorly of the receiver; Fig. 75 8 is a cross-sectional view through the resilient grip sleeve and grounding collar in which the terminal of the electrostatic shield is enclosed; Fig. 9 shows front and side views of the lug which surrounds the 85 resilient grip sleeve connecting the telephone receiver cord terminals with the bobbins within the telephone receiver; Fig. 10 is a front and side view of the grounding collar 90 which completes connections between the electrostatic shield and the casing of the telephone receivers; and Fig. 11 illustrates more particularly the construction of one of the terminals which are provided on the 95 ends of the conducting cords and the electrostatic shield.

Referring more particularly to the drawings reference character 1 designates a telephone receiver casing in which there is disposed electromagnets 2, and permanent magnet 3 secured in position by kidney pieces 4 and 5. Cap 6 fits over the casing 1 forming the housing for the electromagnetic sound reproducer. Terminal block 7 is secured in

position within the casing 1, by means of the kidney pieces 4 and 5 which extend over portions 8 and 9 of the terminal block. The terminal block 7 is constructed of substantially semi-circular portions of insulated material 10 and 11, divided along a horizontal axis 12 and secured together by means of binding screws 14 and 15. Each of the portions 10 and 11 contain cut away portions 16, 17, 18, 19, 20 and 21 which are brought adjacent to each other and form substantially cylindrical bores extending into the terminal block. Positioned within these bores I provide split resilient collar members 22, 23 and 24. The construction of collar members 22 and 24 is shown more particularly in Fig. 5. Each collar member consists of a cylindrical portion which is split longitudinally with the side edges of the collar member parallel with each other throughout their length as represented at 22^a. The collar member 22 is surrounded and gripped by a lug member 25, shown more particularly in Fig. 9. The lug member 25 consists of a sheet of material which is bent upon itself with its faces pressed into contact with each other along its portion 25^a and bent into a substantially circular portion 25^b which encloses and grips the collar member 22. The lug member 25 is open at point 25^c to enable the resilient grip sleeve 22 to readily increase or decrease in its effective diameter. The upstanding portion 25^a serves as a connecting lug for the magnet windings of the telephone receiver. The telephone receiver cord 26 is provided with terminal member 27 having a longitudinally extending cylindrical portion 28 and a spherical head portion 29 at the end thereof. Interiorly of the resilient grip sleeve 22, I provide an inwardly extending annular ring 22^b which is arranged to grip the neck portion 30 between the spherical portion 29 and the neck 30. The resilient grip sleeve 22 is provided with an annular flange 22^c against which the circular portion 25^b of lug 25 abuts forming a substantial support for the upwardly extending lug which passes through apertures in the portion 10 of the terminal block. The electrostatic shield which surrounds the telephone cords terminates in connection 31, illustrated in Figs. 6 and 8 with a terminal tip 32 thereon. Resilient grip sleeve 33 is mounted within the bore 23 generally similar in construction to the collar 22. A ground lug 34, as rep-

resented more particularly in Fig. 10, surrounds the resilient grip sleeve 33 and extends downwardly through the portion 11 of the terminal block 7 as indicated at 35 in Fig. 4 and contacts with the casing 1 of the telephone receiver. In this way a connection is completed from the electrostatic shield to the casing of the telephone receiver. The collar 34 is constructed from a flat strip of material pressed together at 34^a and formed in a cylindrical portion 34^b with the edges 34^c spaced apart to allow expansion and contraction of the resilient grip sleeve 33 for making a snap connection between the tip 32 and the terminal 33.

I have illustrated my invention in one of its preferred embodiments, but I desire that it be understood that other modifications may be made and that no limitations upon the invention are intended other than are imposed by the scope of the appended claims.

What I claim and desire to secure by Letters Patent of the United States is:

1. A terminal block, a plurality of resilient-sleeve-like contacts therein, said block and said contacts having aligned entrances located at one side of said block to admit a plurality of terminal tips, each of said contacts comprising a split cylindrical portion with an inwardly extending annular ridge adjacent one end thereof, and a collar member extending around each of said contacts and having extended portions passing through said block to provide a lug by means of which an electrical conductor may be connected to the contacts, each of said tips comprising a cylindrical portion and a spherical head separated by a neck portion, said neck portion being arranged to be gripped by said annular ridge within said sleeve-like contacts when said terminal tips are forced into said sleeve-like contacts.

2. A terminal block of insulating material, a pair of resilient sleeve-like contacts therein, a similar contact in said block parallel to and between said pair of contacts, a collar member gripping each of said pair of contacts and having an extension thereon extending upwardly through said block to provide a binding lug, and a collar member gripping said intermediate contact and having an extension thereon extending downwardly through said block.

In testimony whereof I affix my signature.
NICHOLAS J. CELENZA.
